CLAIM

The ornamental design for a fork lift with movable control console, as shown and described.

DESCRIPTION

The design is described in the accompanying drawings wherein; The file of this patent contains at least one drawing executed in color.

FIG. 1 is a front perspective view of the mobile lift which forms the subject of this invention;

FIG. 2 is a rear perspective view of the device of FIG. 1; FIG. 1 is a front perspective view of the mobile lift which forms the subject of this invention;

FIG. 4 is a view similar to FIG. 3 with the control console having been rotated to a different position; and,

FIG. 5 is a view similar to FIG. 1 with the control console having rotated.

The undisclosed left side of the forklift is the same as the side shown in FIGS. 1-5 except that the logo is not included and the rear side of the control console is seen which is plain and unornamented.
